UNITED STATES PATENT OFFICE.

WILLIAM A. DOBSON, OF BRIDGEPORT, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed January 23, 1923. Serial No. 614,399.

To all whom it may concern:

Be it known that I, WILLIAM A. DOBSON, a citizen of the United States, residing in Bridgeport, in the county of Fairfield and State of Connecticut, have invented certain new and useful Improvements in Typewriting Machines, of which the following is a specification.

The present invention relates to typewriting machines of the class in which the platen is on a carriage movable in letter-feed and return directions with respect to a fixed printing point, and in which the type-bars strike on the front of the platen. More particularly, the invention relates to means for finding the correct location of the carriage for printing in any desired letter, or column, position.

It is usual to provide a typewriting machine with a scale set close to the surface of the platen at the printing line, to designate the position, in the line, of a letter or character written in registration therewith, and to serve as a gage both in letter-space and line-space adjustments of the paper on the platen. This scale has heretofore been relied upon also as a means whereby to set the platen with any desired letter or column position thereof at the printing point. In order, however, reliably to fulfill its first-mentioned functions, it must be set in such position that, in a front-strike machine, it passes behind the type-guide and ribbon, at and near the printing point; and is, therefore, readable with uncertainty and trouble at just the part thereof which is of consequence in setting the carriage for printing in a given letter or column position.

A feature of the invention is the provision of means whereby the setting of the platen-carriage for printing in a desired letter or column position, may be correctly and quickly determined.

In this connection, a feature of the invention is a second or auxiliary scale, secured to the carriage below the usual scale, and in such position that view of the portion thereof at and near the printing point is unobstructed by the type-guide and ribbon. The plate or piece on which the type-guide proper is formed, is preferably utilized to provide an index point or finger, exactly in line with the printing point, for registration with the

graduations on this second scale, and, for this purpose, may have an opening therein under the type-guide proper, and through which the scale is visible; the index-point being formed on that edge of the guide-piece which forms the lower wall of the opening therethrough.

Typewriting machines are usually provided with spring-fingers for holding the margins of the paper to the platen above the printing line; these fingers being secured to the carriage below the usual scale, projecting upward across the front of the latter, and being carried by slides on a rail, for adjustment lengthwise of the platen.

A feature of the invention is the use of this rail as the support for the second scale. Another feature of the invention is the formation of the second scale as a spring-strip having a natural set such that, when free, it assumes a form in which the front of the scale is concave, and, when secured at its ends to the rail, it lies flat, and bears resiliently, against the latter, throughout its length. The spring-scale may therefore, be laid on the rail over the finger-carrying slides; and, bearing resiliently toward the rail, will permit movement of the slides between the same and the rail, and will exert a pressure on the slides sufficient to hold the latter by friction against accidental displacement.

The scale may be otherwise mounted, and may be so spaced from the ordinary scale as to allow the paper-fingers to project between the two scales. The two scales may be in a single piece, and the single piece may be slotted to allow the paper-fingers to project therethrough and to be adjustable therewith.

When the paper is long, or where, as in the case of the so-called portable machines, the machine is of little height, the end of the paper may drag on the machine-support or desk, unless provision to the contrary is made. Paper-supporting fingers, forming in effect an upward extension of the paper guide or table at the rear of the platen, are commonly provided to prevent contact of the paper with the desk; and these fingers are usually collapsible or foldable to idle position when not in use.

A feature of the invention is a novel and simple pivotal mounting of these paper-sup-

porting fingers, and construction of the fingers at their pivots, for assuring easy movement thereof, and for assuring their position, against unintentional movement, 5 whether in effective or in idle position.

Other features and advantages will hereinafter appear.

In the accompanying drawings,

10 Figure 1 is a top plan view of the platen-carriage and parts carried thereby; certain of the parts being broken away for clearer illustration of underlying parts.

15 Figure 2 is a view, in front elevation, of the platen-carriage and parts carried thereby; the type-segment, type-guide, and auxiliary scale being also shown.

Figure 3 is a perspective view of the auxiliary scale in relaxed condition.

20 Figure 4 is a view, in cross-sectional side elevation, taken on the line 4—4 of Figure 1.

Figure 5 is a view similar to Figure 4, except that the shift-frame and main frame are omitted, the supplemental paper-supports shown in effective position, and the pressure- 25 rolls in released position.

Figure 6 is a view showing one of the supplemental paper-supports folded down into the position assumed when not in use.

30 The platen 10 is revolvably mounted in the side plates 11 and 12 of the platen-carriage 13. The carriage is movable in letter-feed and return directions on a case-shift-frame 14, and is movable as a unit up and down with the latter from one to another case- 35 position on the main frame 15. The mounting of the shift-frame on the main frame and the means by which the shift is effected may be that shown in United States Letters Patent to William A. Dobson, No. 1,335,956, 40 dated April 6, 1920, to which reference is

made for such understanding thereof as may be desired. The carriage side plates 11 and 12 are connected at the rear by a cross piece or tie 16, and, below the platen, by another 45 cross piece or tie 17. The cross-pieces 16 and 17 are themselves connected, intermediate their ends, by two straps 17' (see Figure 5). The cross-piece 17 is supported by roller- 50 bearings 18 on a rail or runway 19 on the shift-case-frame. A roller 20, carried by a bracket-arm 21, secured to the cross-piece 17, engages the under side of the rail 19, to hold the forward part of the carriage to the rail 19. A bracket 22 on the carriage-cross- 55 piece 16 carries a roller 23, by means of which the carriage is supported at its rear on a rail 24, formed on the upper edge of a rear cross-piece 25 of the shift-frame 14. A lip 26 in the lower end of the bracket 22 is 60 turned under the rail 24, to prevent upward displacement of the rear of the carriage.

Secured to the carriage-cross-piece 17, as by screws 27, one at each side thereof, are sheet-metal brackets 28, having arms 29 formed 65 thereon. The ends of these arms are bent

over, as at 30, to receive and hold pins or shafts 31, on which the usual paper table and apron 32 is pivoted; the paper-table having ears 33, turned down, from either end thereof, to receive the pins 31. As shown in the 70 drawings, the paper-table 32 may be rocked around its pivots 31 between Figures 4 and 5 positions. Set in curls 34, in the lower forward edges of the paper-table and apron 32, are the shafts 35 of the pressure-feed-rolls 75 36. In Figure 4 position of the paper-table, the rolls 36 bear upon the platen for feed of the paper with the latter. In Figure 5 position of the paper-table, the pressure-rolls are shown as released from the platen, to permit 80 of easy insertion, removal and adjustment of the paper. For throwing the paper-table from Figure 4 to Figure 5 position, to release the rolls, an arm 37 is provided. This arm has a lateral offset 38 at its upper end 85 (see Figure 1), which carries a roller 39 for frictionless engagement with the rear of the paper-table. The arm 37 is fast to, or forms an offset on the end of, a rock-shaft 40. The rock-shaft 40 has a bearing formed on the 90 one hand by the flange 41 of the carriage-cross-piece 16, and on the other hand by rounded grooves 42 in the heads of screws 43, threaded into the carriage-cross-piece 16. The rock-shaft 40 extends 95 longitudinally of the carriage, and, at its right-hand end, has fast thereto, or turned up therefrom, an arm 44, which carries a finger-piece 45. Forward movement of the finger-piece 45 from Figure 4 to Figure 5 100 position causes the rock-shaft 40 to throw the arm 37 forward and downward against the table 32, to rock the latter on its pivot 31 in such direction as to release the pressure-rolls. 105

The table is held in Fig. 4 position, and is returned from Figure 5 to Figure 4 position, and the pressure of the rolls 36 against the platen, in Figure 4 position, is maintained by means of leaf-springs 46, one at each end of the paper-table. These springs 46 (see Figures 1 and 5), at one end, are secured by screws 47 to the under side of the carriage-cross-piece 17. They are thence extended rearwardly and upwardly, and thence forwardly between the pin-shafts 31 and the paper-table, and their free ends 48 are continued forwardly along the under side of the paper-table, in contact with the latter, and of the general curvature of the latter. In the Figure 4 position of the paper-table, these springs are under sufficient compression to exert a pressure of the feed-rolls on the platen. In the Figure 5 position of the paper-table, the springs are under further compression and tend to throw the paper-table and the rolls off the platen. In this position of the paper-table, however, the return thereof to Figure 4 position is blocked by the arm 37 and roll 39, which, as shown in Fig. 110 115 120 125 130

ure 5, are in dead-center position in respect to the table.

The fingers for supporting the paper, and forming, in effect, an upward extension of the paper-table 32, are in the form of metal strips 49, pivoted on ears 50, formed on the flange 41 of the carriage-cross-piece 16. In their ineffective or Figures 1 and 4 position, they are folded down, parallel to the carriage-cross-piece 16. To be brought into use, they are swung up by means of ears or finger-pieces 51, formed thereon, to Figure 5 position. A screw 52, threaded into the corresponding bracket-ear 50, serves as a pivot for each finger 49. This screw has an enlarged portion 53, which provides a shoulder, and has bearing on a washer 54, inserted between the same and the bracket-ear 50. The enlarged portion 53 passes through an opening in a bent-out or bellied-part 55 of the finger, and terminates in a head 56. The finger, at each edge of its bellied portion 55, bears against the washer 54, and is held against forward and rearward angular displacement by the washer and by the head 56 of the screw. When the screw is turned down to bring the shoulder of the enlarged portion 53 thereof against the washer, the head 56 bears upon the bellied portion 55 of the finger, and, the latter being somewhat resilient, a grip of the finger by the screw is obtained; such as to cause the finger to be held by friction in whatever position it may be set, without, however, unduly resisting movement of the finger. The finger is, therefore, prevented from falling from its effective position, and, when the machine is tilted, will not swing outward from ineffective position. The washer 54 may be threaded to serve as a lock-nut for the screw 52. The washer 54 presents a smooth facing for the bracket 50 and a smooth bearing surface on which the finger is swung. The washer itself is, however, prevented from turning by means of a pin 57, set into an indentation in the edge thereof (see Figure 6), and into the bracket-ear 50. The pin 57, by engagement with the edge of the finger 49, serves as a stop to determine the ineffective position of the finger, as shown in Figure 6. When the finger is thrown to Figure 5 position, the edge of a tail-piece 58 on the finger strikes the other side of the pin 57 to determine the position thereof at right angles to the carriage-cross-piece 16.

The machine is shown as a front-strike machine, and the types 59 are pivoted in the usual manner to a segment-plate 60, stationary on the main frame of the machine. Made fast by screws 61 to the segment-plate 60 is a type-guide 62. Fingers 63 on the type-guide define a passage 64, for receiving a shoulder on the type-bar to guide and center the type. The usual letter-space-scale 65

is provided with ears 66, turned rearward and extending downward from the lower edge thereof, and these ears are set against, and secured by screws 67 to, ears 68, offset downward from the front edge of the paper-table. When, therefore, the paper-table is moved from Figure 4 to Figure 5 position, the scale 65 is thrown downward and away from the platen, to permit free movement of the sheets around the platen, between the scale and the platen, and to permit of lateral adjustment of the sheets with respect to the graduations on the scale. The scale ordinarily also serves as a line-gage.

It will be noted, however, that at, and in the immediate vicinity of, the printing point (see Figure 2), the portion 69 of the type-guide, which supports the fingers 63 thereof, partially obstructs the view of the scale 65. Even when the ribbon is not present, the scale cannot be easily read through the type-guide-groove 64, because of the depth of the latter and the distance of the scale behind the type-guide, and because of the insufficiency of light behind the type-guide. When the ribbon is present, it may obstruct any view of the scale behind the type-guide, unless the scale is provided with graduated wings projecting above the ribbon. Visible numbering of graduations on such wings is not ordinarily provided, and, in any event, the wings must be separated and the graduations thus interrupted to permit of passage for the type to the platen. With or without the ribbon, a quick and certain reading of the scale 65, for placement of a desired graduation thereon at the printing point, is difficult.

In order that any desired point or letter-position in a line may be accurately and assuredly set at the printing point by movement of the platen with the paper thereon in letter-feed or reverse direction, a second scale 70 is provided. This scale is secured at its ends by screws 71 to a rail 72. The rail 72 is held fixed on the paper-table by means of the screws 67, and is the rail which carries the usual spring-fingers 73, for holding the paper to the platen above the printing line. Each finger 73 is unitary with a slide 74, set against the rail 72, and slidably held thereto by ears 75, bent over and around the upper and lower edges of the rail 72. The fingers 73 may, therefore, be moved laterally along the rail 72 for marginal engagement with paper of different widths. The supporting ears 66 on the scale 65, which are spaced from the rail 72 by shoulders or lugs 76 on the latter, are offset forward, over the upper edge of the rail 72, clearance being provided between the ears 66 of the scale 65, and the ears 75 which hold the paper-finger-slides 74 to the rail 72.

The second scale 70 is set to the rail 72 with the paper-finger-slides 74 between the

5 rail 72 and the scale 70. The scale 70, as indicated in Figure 3, is a strip of spring-metal, which, when relaxed, tends to curve forward from the center of the scale to the 10 ends thereof. When, therefore, it is secured by the screws 71 to the rail 72, it sets snugly against the rail 72 throughout its length, and exerts a resilient pressure on the slides 74 of the paper-fingers, tending, by friction, to hold the paper-fingers 73, against displacement, in whatever position the fingers 73 may be set. The attachment of the scale 70, being at the ends thereof, and the scale being 15 resilient, the slides 74 of the paper-fingers may be moved freely lengthwise of the platen between the scale 70 and the rail 72.

20 The scale 70 may be accurately adjusted in respect to the scale 65, to bring the readings on the two scales into proper registration, by reason of the fact that the openings 25 77 in the scale 70, through which the screws 71 pass, are elongated. When the screws 71 are loosened, the scale 70 may be adjusted longitudinally with respect to the scale 65, and, when the heads of the screws 71 are 30 tightened against the scale 70, the latter will be held fast in adjusted position. Slots 78 in the downward offsets 68 of the paper-table provide for similar adjustment of the scale 65.

35 It will be noted that an opening 79 is provided in the type-guide-plate 62 below the upper cross-piece 69 of the latter, and that this opening is of such width and so located 40 that the scale 70, with its graduations and numerals, is clearly visible to the operator therethrough, below the lower edge of the ribbon. The wall which forms the lower edge of the opening 79 has an index point or 45 finger 80, centrally thereof and in true alignment with the printing position. The letter-space position of the platen and paper, with respect to the printing point, may, therefore, at all times, be accurately determined by means of the scale 70 and index-point 80; there being nothing at any time 50 to obstruct view of the scale 70 at the index-point 80.

55 Variations may be resorted to within the scope of the invention, and portions of the improvements may be used without others.

Having thus described my invention, I claim:

1. In a front-strike typewriting machine, 60 type-bars, a type-segment to which the bars are pivoted, a type-guide for the bars at the printing point, a platen, a platen-carriage, a letter-space-scale on the carriage behind the type-guide, close to the surface of the platen, marginal paper-fingers secured to the carriage below the scale, projecting upward across the same for engagement with the platen above the printing line, and a second scale set over the fingers and behind the 65 type-guide, below the first scale, and having

the graduations thereon visible at the printing point below the type-guide.

2. In a front-strike typewriting machine, 70 type-bars, a type-segment to which the bars are pivoted, a type-guide for the bars at the printing point, a platen, a platen-carriage, a letter-space-scale on the carriage behind the type-guide, close to the surface of the platen, a rail below the scale, marginal paper-fingers 75 slidable on the rail and projecting upward over the scale for engagement with the platen above the printing line, and a second scale set upon and secured to the finger-supporting rail, and having the graduations thereof visible at the printing 80 point below the type-guide.

3. In a front-strike typewriting machine, 85 type-bars, a type-segment to which the bars are pivoted, a type-guide for the bars at the printing point, a platen, a platen-carriage, a letter-space-scale on the carriage behind the type-guide, close to the surface of the platen, a rail below the scale, marginal paper-fingers 90 slidable on the rail and projecting upward over the scale for engagement with the platen above the printing line, and a second scale set upon and secured to the rail over the paper-fingers, and having the graduations thereof visible at the printing 95 point below the type-guide.

4. In a front-strike typewriting machine, 100 type-bars, a type-segment to which the bars are pivoted, a type-guide for the bars at the printing point, a platen, a platen-carriage, a letter-space-scale on the carriage 105 behind the type-guide, close to the surface of the platen, a rail below the scale, marginal paper-fingers slidable on the rail and projecting upward over the scale for engagement with the platen above the printing line, and a second scale set upon and secured to the rail over the paper-fingers, and having the graduations thereof visible at the printing 110 point below the type-guide, the second scale being secured to the rail at the 115 ends thereof, to permit movement of the fingers along the rail between the rail and the scale thereon.

5. In a front-strike typewriting machine, 120 type-bars, a type-segment to which the bars are pivoted, a type-guide for the bars at the printing point, a platen, a platen-carriage, a letter-space-scale on the carriage behind the type-guide, close to the surface of the platen, a rail below the scale, marginal paper-fingers 125 slidable on the rail and projecting upward over the scale for engagement with the platen above the printing line, and a second scale set flat against and secured to the rail over the paper-fingers, and having the graduations thereof visible at the printing point below the type-guide, the second scale being flexible to permit movement of the fingers along the rail.

6. In a front-strike typewriting machine, 130

type-bars, a type-segment to which the bars are pivoted, a type-guide for the bars at the printing point, a platen, a platen-carriage, a letter-space-scale on the carriage 5 behind the type-guide, close to the surface of the platen, a rail below the scale, marginal paper-fingers slideable on the rail and projecting upward over the scale for engagement with the platen above the printing line, 10 and a second scale set flat against and secured to the rail over the paper-fingers, and having the graduations thereof visible at the printing point below the type-guide, the second scale being of spring-metal having a 15 set such that, when released from the rail, it presents a concave front face, and such that, when set flat against the rail, it exerts a resilient pressure on the fingers, serving to hold the fingers by friction in adjusted 20 position.

7. In a front-strike typewriting machine, type-bars, a type-segment to which the bars are pivoted, a type-guide for the bars at the printing point, a platen, a platen-carriage, 25 a letter-space-scale on the carriage behind the type-guide, close to the surface of the platen, a rail below the scale, slides on the rail, marginal paper-fingers carried by the slides, and projecting upward over the scale 30 for engagement with the platen above the printing line, and a second scale set flat against and secured to the rail over the slides, and having the graduations thereof visible at the printing point below the type- 35 guide, the second scale being of spring-metal having a set such that, when released from the rail, it presents a concave front face, and such that, when set flat against the rail, it exerts a resilient pressure on the slides, 40 serving to hold the fingers by friction in adjusted position.

8. In a front-strike typewriting machine, type-bars, a type-segment to which the bars are pivoted, a type-guide for the bars at the printing point, a platen, a platen-carriage, 45 a letter-space-scale on the carriage behind the type-guide, close to the surface of the platen, a rail below the scale, marginal paper-fingers slideable on the rail and projecting upward over the scale for engagement 50 with the platen above the printing line, and a second scale set flat against and secured to the rail over the paper-fingers, and having the graduations thereof visible at 55 the printing point below the type-guide, the second scale being of spring-metal having a set such that, when released from the rail, it presents a concave front face, and such that, when set flat against the rail, it will 60 yield forward to accommodate the fingers.

9. In a typewriting machine, a platen, a platen-carriage, a rail on the carriage in front of the platen, and extending longitudinally thereof, and a scale set upon and secured to the rail; the scale being a graduat- 65

ed spring-metal strip having a set such that, when free of the rail, it bends to present a concave front face, and such that, when secured by its ends to the rail, it will lie flat against the latter throughout the length of 70 the same.

10. In a typewriting machine, a platen, a platen-carriage, marginal paper-fingers adjustable on the carriage lengthwise of the platen, and projecting upward for engagement with the platen above the printing line, and a duplex scale secured to the carriage at the front of the platen, and extending longitudinally of the latter; the scale having identically graduated sections with an elongated opening therebetween through which the paper-fingers project, and along which the paper-fingers may be adjusted. 75 80

11. In a typewriting machine, type-bars, a type-guide, a platen, a platen-carriage, marginal paper-fingers adjustable on the carriage lengthwise of the platen, and projecting upward for engagement with the platen above the printing line, and a duplex scale secured to the carriage at the front 90 of the platen, and extending longitudinally of the latter; the scale having identically graduated sections with an elongated opening therebetween through which the paper-fingers project, and along which the paper-fingers may be adjusted; one of said scale-sections being close to the surface of the platen behind the type-guide, and the other of the scale-sections being visible below the 95 type-guide. 100

12. In a typewriting machine, type-bars, a type-guide, a platen, a platen-carriage, marginal paper-fingers adjustable on the carriage lengthwise of the platen, and projecting upward for engagement with the 105 platen above the printing line, a duplex scale secured to the carriage at the front of the platen, and extending longitudinally of the latter; the scale having identically graduated sections with an elongated opening therebetween through which the paper-fingers project, and along which the paper-fingers may be adjusted; one of said scale-sections being close to the surface of the platen behind the type-guide, and the other 110 of the scale-sections being visible below the type-guide; and an index point or finger at the printing point for registration with the graduations on the lower scale-section. 115

13. In a front-strike typewriting machine, the combination with a revoluble platen and ribbon-mechanism including a type-guide, of a letter-feed and aligning scale extending along the platen adjacent the printing line, a second scale beneath the first-named scale and having corresponding graduations therewith, said second scale being visible beneath the type-guide, and paper-fingers slidably mounted at the front 120 of the platen, one of said scales co-operating 125 130

with said paper-fingers to hold the latter frictionally in adjusted positions along the platen.

14. In a front-strike typewriting machine, the combination with a revoluble platen and ribbon-mechanism including a type-guide, of a letter-feed and aligning scale extending along the platen adjacent the printing line, a second scale visible beneath the first scale and having correspond-

ing graduations therewith, an index associated with said type-guide and registering with said second scale whereby to indicate the letter-feeding position of the platen, and paper-fingers mounted to slide lengthwise in front of the platen, said second scale frictionally engaging said paper-fingers, whereby to hold the latter in adjusted positions along the platen. 15

WILLIAM A. DOBSON.
